DISPENSING DEVICE

Jesse W. Boisseau, Dallas, Tex., assignor of one-half to S. D. Bowles, Dallas, Tex.

Application February 19, 1938, Serial No. 191,407

2 Claims. (Cl. 221—23)

This invention relates to new and useful improvements in dispensing devices.

One object of the invention is to provide an improved dispensing device for dispensing liquid from a sealed can, said device being particularly adapted for use in dispensing a lubricant, generally known to the trade as "top lube", but being applicable to other uses.

An important object of the invention is to provide an improved dispenser which is made in the form of a funnel adapted to receive a sealed can of lubricant and having a cutter therein for puncturing the can to decant the contents; there also being improved means for forcing the can into the funnel to engage the cutter, whereby the can may be quickly punctured and emptied.

A further object of the invention is to provide a dispensing device, of the character described, having a handle which facilitates handling of the device, said handle being associated with a pivoted lever which is arranged to engage the inserted can to force the same into the device to puncture said can.

Still another object of the invention is to provide an improved dispenser for dispensing liquids from sealed containers which is constructed of a minimum amount of material and which is simple and inexpensive in manufacture.

A construction designed to carry out the invention will be hereinafter described, together with other features of the invention.

The invention will be more readily understood from a reading of the following specification and by reference to the accompanying drawing, in which an example of the invention is shown, and wherein:

Figure 1 is a view, partly in section and partly in elevation of a dispensing device, constructed in accordance with the invention.

Figure 2 is a horizontal, cross-sectional view, taken on the line 2—2 of Figure 1, and

Figure 3 is an isometric view of the device.

As is well known, it has become the practice in recent years of manufacturers of lubricants, and the like, to put up the products in hermetically sealed cans so as to insure the motorist securing the proper lubricant for his vehicle. The hermetically sealed cans are opened in the presence of the purchaser and are discharged into the gas tank of the vehicle. The device herein shown has been designed particularly for small cans which contain a lubricant known generally as "top lube" which is emptied into the gas tank and admixed with the gasoline.

This "top lube" serves to lubricate the valves of the engine. However, the devices may be used for other purposes.

In the drawing, the numeral 10 designates a funnel which includes a cylindrical collar portion 11. The collar portion is cylindrical and has a depending skirt 12 and a portion of the wall of said skirt forms an extension of the collar portion, while the remainder of the skirt wall, as indicated at 13, is inclined or tapered inwardly. The skirt is, of course, open at its lower end, whereby a liquid which is poured into the collar portion escapes through the open or outlet end 14. An extension 15 is preferably made integral with the collar portion 11 and extends upwardly therefrom. This extension is arcuate in cross-section and is gradually reduced toward its upper end. The upper portion of the extension 15 is thickened as shown at 16 and an inclined handle 17 is made integral with this thickened portion. As is clearly shown in Figures 1 and 3, the handle extends upwardly at an inclination. A lever 18 is pivoted on a bolt 19 which extends through an opening 20 formed at the inner end of the handle 17. The lever is formed with a curved portion 21 which extends inwardly over the extension 15 and also overlies the funnel. The extremity 22 of the curved portion 21 is located in substantially axial alignment with the collar portion 11 of the funnel. 30

Located within the collar portion 11 is a curved cutting blade 23 and this blade is spaced from the inner wall of said collar by a spacing strip 24. A bolt 25 extends through the wall of the collar, through the strip 24 and through the lower portion of the cutting blade 23, and receives a nut 26, whereby the blade is securely fastened in position within the collar.

In using the device, a hermetically sealed can has one end inserted within the collar portion 11, whereby its top or bottom, as the case may be, engages the pointed end of the cutter blade 23. The lever 18 is swung so that the extremity 22 of the curved portion formed on the lever, engages the upper end of the can. The operator then grasps the lever and handle 17 in one hand and squeezes or moves said lever and handle toward each other. Since the handle 17 is stationary, the outer end of the lever 18 swings upwardly on the pivot 19, thereby causing the inner end of said lever to swing downwardly. Since this inner end is engaging the can, such swinging of the lever will cause the can to be forced downwardly within the collar portion, whereby the blade 23 punctures or cuts the end 55

- of said can. This position of the can is shown in dotted lines in Figure 1. After the can is punctured, it will be manifest that its contents will flow from the can and into the funnel formed by the skirt 12 which depends from the collar portion 11. The outlet end 14 of the funnel is, of course, inserted into the gas tank inlet so as to permit the contents of the can to flow into said tank.
- 10 The arrangement of the lever 18 and the handle 17 permits the device to be readily handled by the operator and said operator need only use one hand. The lever provides a positive means for forcing the can downwardly into engagement with the cutter blade 23. It is noted that the construction of the device is such that a minimum amount of material need be employed. The arcuate extension 15 is only sufficiently large to guide the can into the collar portion 11. Manufacture of the device is greatly simplified by inclining only a portion of the wall of the skirt 12, the remainder of said wall being substantially vertical.
- 15 20 25 What I claim and desire to secure by Letters Patent is:

1. A dispensing device for hermetically sealed containers including, a cylindrical collar portion adapted to receive the end portion of the container, a skirt integral with and depending from the collar portion, said skirt having its lower end reduced to form a funnel, a cutter located within the collar portion and fastened thereto, said cutter being arranged to puncture the container when the same is forced downwardly into the collar portion, an integral extension pro-

jecting upwardly from the collar portion, an inclined handle extending outwardly from the upper end of the extension, and a lever pivoted on the inner end of the handle and having its inner end overlying the container within the collar portion, the outer end of said lever being so located that both lever and handle may be grasped in one hand to swing the lever and thereby force the container downwardly into engagement with the cutter.

2. A dispensing device for hermetically sealed containers including, a cylindrical collar portion adapted to receive the end portion of the container, a skirt integral with and depending from the collar portion, said skirt having its lower end reduced to form a funnel, a cutter located within the collar portion and fastened thereto, said cutter being arranged to puncture the container when the same is forced downwardly into the collar portion, an integral extension extending vertically from one side of the collar portion and being curved in cross-section so as to fit the side of the container when the same has its end portion within the collar, an inclined handle extending outwardly from the upper end of the extension, and a lever pivoted on the inner end of the handle and having its inner end overlying the container within the collar portion, the outer end of said lever being so located that both lever and handle may be grasped in one hand to swing the lever and thereby force the container downwardly into engagement with the cutter.
